(57) **CLAIM**

The ornamental design for a hair clip, as shown and described.

DESCRIPTION

FIG. 1 is a perspective view of a hair clip according to a first embodiment showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view thereof showing the device in another side;

FIG. 9 is a perspective view showing the hair clip in the open position;

FIG. 10 is a perspective view of a hair clip according to a second embodiment showing my new design;

FIG. 11 is a front elevation view of the second embodiment thereof;

FIG. 12 is a rear elevation view of the second embodiment thereof;

FIG. 13 is a left side elevation view of the second embodiment thereof;

FIG. 14 is a right side elevation view of the second embodiment thereof;

FIG. 15 is a top plan view of the second embodiment thereof;

FIG. 16 is a bottom plan view of the second embodiment thereof;

FIG. 17 is a perspective view of the second embodiment thereof showing the device in another side; and,

FIG. 18 is a perspective view of the second embodiment showing the hair clip in the open position.

(Continued)

The broken lines depict portions of the hair clip, which form no part of the claimed design.
